UNITED STATES PATENT OFFICE.

JUSTIN KAY TOLES, OF SAN FRANCISCO, CALIFORNIA, ASSIGNOR TO WILLIAM R. BROWN, OF DETROIT, MICHIGAN.

FIBER-CLEANING APPARATUS.

1,115,990.

Specification of Letters Patent.

Patented Nov. 3, 1914.

Application filed July 23, 1913. Serial No. 780,838.

To all whom it may concern:

Be it known that I, JUSTIN KAY TOLES, a citizen of the United States of America, residing at San Francisco, county of San Francisco, State of California, have invented a certain new and useful Fiber-Cleaning Apparatus; and I do hereby declare the following to be a full, clear, and exact description of the invention, such as will enable others skilled in the art to which it appertains to make and use the same.

This invention relates to fiber cleaning apparatus, and it may be said to consist in the provision of the novel and advantageous features and in the novel and improved construction, arrangement and combination of parts and devices as will be apparent from the description and claims which follow hereinafter.

One object of the invention is to provide novel and improved means for guiding the fibrous material through the apparatus from the intake end to the discharge end of the apparatus.

Another object of the invention is to provide novel and improved means for causing the fibrous material to follow a definite course through the apparatus.

A further object of the invention is to provide novel and improved means whereby the fibrous material while being treated in the apparatus is constrained to proceed in a substantially helical direction.

A further object of the invention is to provide novel and improved means for preliminarily cleaning a portion of the fibrous material as the latter is being fed into the apparatus.

A further object of the invention is to provide a novel and improved stationary device which surrounds the rotor and is adapted to guide the fibrous material and to coact with the rotor to clean the fibrous material.

Further objects of the invention are to provide apparatus of the class specified, which is simple in character, economical to construct, maintain, and use, easy to operate, strong and durable, positive and certain in its action, efficient in service, produces long fiber, and which is generally superior and better from a commercial standpoint than existing apparatus of this class.

Other objects and the advantages of the invention will be apparent to those skilled in the art, from a consideration of the follow-

ing description of the preferred form of construction taken in connection with the accompanying drawings in which—

Figure 1 is a front elevational view of the apparatus; Fig. 2 is a plan view of the apparatus; Fig. 3 is an enlarged sectional view taken on the line 3—3 of Fig. 1; Fig. 4 is an enlarged partly broken and sectional view taken on the line 4—4 of Fig. 3; Fig. 5 is a broken and sectional view taken on the line 5—5 of Fig. 4; Fig. 6 is an enlarged partly broken and sectional view showing one of the air inlet doors in open position on the casing; Fig. 7 is an enlarged plan view of the cage which surrounds the rotor, the scraping bars being omitted; Fig. 8 is an enlarged broken and sectional view taken on the line 8—8 of Fig. 7 and showing the scraper bars; Fig. 9 is a plan view of a portion of the cage; Fig. 10 is an enlarged sectional view taken on the line 10—10 of Fig. 9; Fig. 11 is an enlarged broken and sectional view taken on the line 11—11 of Fig. 10; Fig. 12 is an enlarged broken and sectional view taken on the line 12—12 of Fig. 1; Fig. 13 is an end elevational view of the rotor; Fig. 14 is a plan view of the rotor; Fig. 15 is an enlarged fragmentary view taken on the line 15—15 of Fig. 13; Fig. 16 is an enlarged plan view of a fragment of the rotor; Fig. 17 is an enlarged elevational view of one of the targin pins; Fig. 18 is a top plan view of the same; Fig. 19 is a bottom plan view of the same; and Fig. 20 is a partial longitudinal sectional view of the rotor.

As shown, the rotor 21 is constructed as follows: The shaft 22 is rotatably mounted in suitable bearings 23 and has thereon the driving pulley 24. A plurality of spiders 25 are mounted fast on the shaft 22, and a plurality of spaced inclined timbers 26 having thereon plates 27 are secured on the periphery of the spiders 25 by means of rods 28 which pass through the plates and the timbers and are suitably secured to the hubs 29 of the spiders 25. On the plates 27 are mounted a plurality of targin pins 30 the stems 31 of which are passed through the plates 27 and driven into the timbers 26. The pins 30 may be disposed staggered in one or more rows on the plates 27 and are preferably arranged to present the edge of junction of diverging faces 32, preferably a V-shape, to the material passing through

the apparatus—and they are of such length and positioned relatively to substantially similar stationarily arranged pins 33 hereinafter described, that when the shaft 22 is 5 rotated the ends of the pins 30 pass close to the ends of and substantially in alinement with the pins 33. Curved plates or vanes 34 are disposed between the timbers 26 and they may have the edges thereof suitably secured to the plates 27. The rotor 21 is arranged within a casing 35 which latter is 10 preferably formed of metal and has therein a framework 36 to which is suitably secured timbers 37 having affixed thereon the pins 33.

15 On the framework 36 is mounted a stationary cage 38 which surrounds the rotor 21 and which is formed to provide a longitudinal recess 39 therein, preferably in the upper rear part thereof, and which has 20 thereon means to guide the fibrous material and also means adapted to scrape and clean the fibrous material in coaction with the rotor 21. As shown, the cage 38 is preferably formed of spaced lower substantially 25 semi-circular bars 40 having one end thereof joined to substantially vertical bars 41 and having the other end thereof joined to bars 42 which latter are formed with a circular portion 43 adjacent to the bars 40 and with 30 a horizontal portion 44 adjacent to the vertical bars 41, tie rods 45 passing through the bars 40, 41, and 42, and preferably rectangular scraping bars 46 mounted on the bars 40, 41, and 42. As seen more clearly 35 in Fig. 7 the bars 40 and 42 are arranged to have their junction with each other—at the front of the cage—substantially midway between their junction with the vertical bars 41—at the rear of the cage—whereby they 40 constitute a substantially helical guide for the fibrous material from the inlet opening 47 to a point adjacent to the discharge opening 48 where they may be arranged parallel and in vertical alinement. The bars 45 45 may be joined to the bars 41 and 42 by means of strips 49 extending into grooves in the bars 41 and 42, and bolts 50 which pass through the strips 49 and are secured by nuts 51 to the angle irons 52 affixed to the 50 timbers 37; also the bars 40 and 42 may have thereon strips 53 which are connected by bolts 54 to the I-beams 55 which latter may be secured to the framework 36 and to the ends of the casing 35.

55 At an opening 56 in the casing 35 adjacent to the intake opening 47 in the cage 38, are arranged a pair of suitable spring-pressed grip rollers 57 at the rear end of a suitable conveyer 58 for feeding the fibrous material.

60 As the fibrous material passes into the intake opening 47 it is acted on by the tarding pins 30 of the rotor 21 and it is held back by the grip rollers 57—the peripheral speed of which is considerably less than that of 65 the rotor—so that the pins 30 effect a comb-

ing and cleaning action on the fibrous material (particularly the crop end which is the more difficult to clean) and thus approximately two-thirds of the length of the fibrous material is cleaned before it leaves 70 the grip rollers 57. Inasmuch as the root end of the fibrous material is the more easily cleaned, the beating and tarding it receives on its way to the discharge end of the apparatus effectually completes the cleaning of 75 the fibrous material.

Along the front of the casing 35 are arranged a plurality of hinged air-inlet doors 59 the opening of which is adjustable by engagement of the doors with pivoted 80 notched arms 60 which pass through slots 61 in the doors 59. Adjacent to the lower open part of the casing 35 is arranged a suitable endless apron 62 for conveying away the dust, shive, impurities, etc., which fall to the lower part of the casing as the fibrous material is being treated.

From the foregoing it will be understood that in operation broken fibrous material or straw from breaker rolls (not shown) may 85 be fed by conveyer 58 to the grip rollers 57 where it is given a preliminary cleaning by the pins 30 which raise the material and pull it apart and comb it over the pins 33 which are disposed at the opening 56. After leaving the grip rollers 57 the material is picked up by the rotor 21 and by reason of centrifugal force it is thrown in a stream line against the corners of the scraping bars 46 and it is guided by the bars 40 to the recess 39 where 90 it is thrown free of the rotor, drops down, is again picked up by the rotor, combed against the pins 33 at the rear of the casing and is then dragged by the rotor in a helical direction—in consequence of the guide bars 95 40 and 42—and contacts with the scraping bars 46 and with the teeth 33 at the front of the casing, is again freed from the rotor and drops in the recess 39, etc., until the material has made a sufficient number of revolutions to effect its cleaning by coaction thereon of the rotor and the cage 38, whereupon the cleaned material passes through the discharge opening 48 onto spout 63 and thence may pass to any suitable tow bin, 100 not shown, freed from all woody particles, and in an unbroken, untangled condition. The timbers 26 are preferably inclined to have the pins 30 revolve in planes substantially parallel to the planes of the bars 42. 105 Air is admitted through any or all of the doors 59 and it, by action of the vanes 34, drives the loosened shive and the dust from the fibrous material.

While one form of construction embodying the invention has been particularly illustrated and described, many changes and modifications will occur to those skilled in the art—wherefore the right is reserved to all such changes and modifications as do 110

not depart from the spirit and scope of the invention as defined in the appended claims.

I claim:

1. In fiber cleaning apparatus, the combination of a casing provided with an admission port, a rotor within the casing, a cage arranged adjacent to the rotor and provided with an intake opening in alignment with said port, coacting means on the 10 rotor and on said cage for cleaning the fiber, pins arranged adjacent to said port and extending into said opening, and grip rollers arranged at said port and adapted to hold back the fiber to give it a preliminary cleaning by the rotor and said pins.
2. In fiber cleaning apparatus, the combination of a casing provided with an admission port, a rotor within the casing, pins on the rotor, a stationary cage arranged adjacent to the rotor and provided with an intake opening in alignment with said port, means on said cage adapted to coact with the pins to clean the fiber, means on the cage to guide the fiber, stationarily mounted pins adjacent to said port and extending into said opening, and grip rollers arranged at said port and adapted to hold back the fiber to effect a preliminary cleaning of the fiber by said pins, substantially as described.
3. In fiber cleaning apparatus, the combi-

nation of a casing, a rotor within the casing, a cage surrounding the rotor and formed to provide a recess, coacting means on the cage and the rotor for cleaning the fiber, and 35 spaced bars on the cage for guiding the fiber.

4. In fiber cleaning apparatus, the combination of a casing, a rotor within the casing, pins on the rotor, bars arranged adjacent to the rotor and adapted to guide the fiber, and bars mounted on the first bars and adapted to coact with said pins to clean the fiber.

5. In fiber cleaning apparatus, the combination of a casing, a rotor within the casing, pins on the rotor, bars arranged adjacent to the rotor and adapted to guide the fiber in a substantially helical direction, stationarily mounted pins adjacent to the bars, 50 and means on the bars adapted to coact with said pins to clean the fiber.

In testimony whereof, I have signed my name to this specification in the presence of two subscribing witnesses at San Francisco, 55 county of San Francisco, State of California, this 14th day of July, A. D. 1913.

JUSTIN KAY TOLES.
